UNITED STATES PATENT OFFICE.

VICTOR G. BLOEDE, OF BALTIMORE, MARYLAND, ASSIGNOR OF ONE-HALF
TO JOHN BANCROFT, OF WILMINGTON, DELAWARE.

RECOVERING SPENT ALKALI.

SPECIFICATION forming part of Letters Patent No. 403,869, dated May 21, 1889.

Application filed April 13, 1888. Serial No. 270,553. (No specimens.)

To all whom it may concern:

Be it known that I, VICTOR G. BLOEDE, a citizen of the United States, residing at Baltimore, in the State of Maryland, have invented 5 certain new and useful Processes for the Utilization and Recovery of Spent Alkaline Liquors; and I do hereby declare that the following is a full, clear, and exact description of the invention, which will enable others skilled in 10 to the art to which it appertains to make and use the same.

The object of my invention is the recovery or rehabilitation of spent or waste alkaline liquors, as well as the production incidentally 15 of several valuable residuary products.

In the process of scouring or boiling off yarns and textile fabrics, as well as in many other branches of manufacture, a large amount 20 of alkali is used, which alkali, after having been more or less impregnated with fatty, resinous, and coloring matter, is at the present time allowed to go to waste.

In the manufacture of wood fiber and other processes the nature of which requires that 25 the alkali be of a considerable degree of concentration, the recovery of the alkali in the spent liquor is now effected by the evaporation of said liquor and subsequent incineration or carbonization of the organic impurities 30 contained. This process, now exclusively employed, is not, however, available for the utilization of all classes of liquors, in that the practicability of the evaporation process is limited to comparatively strong alkaline liquors, much stronger, indeed, than any that are 35 used for scouring or other similar purposes.

The advantage of my improved process lies in the fact that it is applicable to liquors of all degrees of concentration, even the weakest 40 liquor practically used being under this system capable of rehabilitation and reutilization.

The principle of my process is based upon 45 the fact that when alkaline liquors highly charged with resinous, fatty, or other organic impurities—such as the liquors produced in the scouring of yarns and textiles, soap-manufacture, and in other branches of the arts—are neutralized with an acid the impurities 50 soluble in the liquor while it is in a caustic

or alkaline state become almost wholly insoluble and separate more or less completely in the form of a sediment or precipitate. Now, if the acid used for such neutralization of the spent lye be one that can subsequently 55 again be rendered insoluble, separated, or extracted from the alkaline base with which it has been caused to combine, it is evident that a ready means for the rehabilitation of such alkaline liquors is presented.

Having now described the general principle upon which my process is based, I will detail the methods I have already successfully employed in practical work.

Taking as a fair example the spent alkaline 65 liquors obtained as a now entirely useless residuum in the scouring of yarns and textile fabrics, these liquors, of a more or less deep red or brown color, usually mark from $\frac{1}{2}^{\circ}$ to 3° Baumé, and consist of caustic or carbonated 70 soda, as the case may be, (or a mixture of both,) in which the coloring-matter and fatty resinous bodies removed from the fiber are held in solution in a state of saponification. These liquors, as they are expelled from the 75 keir or boiling-vessels, are in the execution of my process allowed to flow into any convenient tank or vessel, preferably provided with a mechanical agitator, and sufficient phosphoric acid is added to effect complete 80 neutralization, or until a faint acid reaction of the liquor results. The previously clear liquor becomes turbid by this treatment, and upon being allowed to remain at rest for a short time nearly the entire organic matters 85 previously held in solution subside in the form of a brownish precipitate or may be removed by filtration. This precipitate, consisting largely of fatty and resinous matters which have been separated from their alkaline 90 saponification through the neutralization by the acid, is of some value, and by subsequent refining may be made to yield a grease suitable for lubricating, soap-manufacture, and other mechanical purposes. After the complete 95 subsidence of the precipitate just described the previously highly-colored solution will be found to have been greatly lightened in color, varying from a light wine to a straw shade, and now consists, of course, of a solu- 100

tion of phosphate of soda or potash, as the case may be. Should the further destruction of the coloring-matter it contains be found necessary or desirable, it may readily be effected at this stage of the process by the addition of a small quantity of any of the known powerful oxidizers—for instance, permanganate of potash or soda, nitric acid, or chlorine, or by treatment with bone or wood charcoal. In practice I give preference to the injection of a little chlorine into the liquor, which speedily and completely eliminates the residuary color in the solution. The neutral solution, after the subsidence of all sedimentary matter, is drawn into a second tank or receiver, preferably provided with a mechanical agitator, and to this clear solution is now added sufficient milk of caustic or carbonate of lime, or a mixture of both, to reabsorb the combined acid contained in the solution and to leave the lime in slight excess. In this case (phosphoric acid having been employed) the resultants from the double decomposition of the materials brought into contact are of course basic phosphate of lime and carbonate or caustic soda, or a mixture of both. The clear liquor, after the subsidence of the phosphate of lime, may now be reused like fresh alkali for further scouring operations.

The phosphate of lime obtained as a residuary product may be utilized either by treatment with an equivalent quantity of sulphuric acid to produce an acid-phosphate fertilizer, or it is entirely decomposed with sulphuric acid in the known manner for the recovery and reuse of the phosphoric acid as such.

Most of the works producing spent alkaline liquors have appliances for the causticization of the soda from its carbonate, and the refuse

or sludge resulting from this operation, and consisting of mixtures of carbonate and caustic lime more or less charged with soda, now forms a very objectionable and expensive residuum. This in my process is very profitably utilized as a precipitant for the phosphoric acids in the operation of recovery. By such use of the lime sludge it will be seen that a very complete utilization of all of the active agents is insured and the highest possible economy achieved. Finally, the fatty bodies contained in the sedimentary matter obtained in the neutralization of the alkaline liquors may be purified by melting and clarifying or in any other convenient way, and can then be utilized for a number of purposes. 55

What I claim as my invention is—

The process herein described for the recovery or rehabilitation of spent alkaline liquors, consisting of the following steps: first, the saturation or supersaturation of said liquors with phosphoric acid, thereby effecting the precipitation of the fatty and coloring matters; second, decanting or filtering the liquor from the separated impurities; third, when found desirable, destroying the residuary color in the decanted liquor with chlorine or its equivalent, and, fourth, subjecting the clarified liquor to the action of lime, barium, or other equivalent compounds capable of entering into an insoluble combination with or extracting the phosphoric acid and liberating the soda or potash in an available form as carbonate or hydrate. 65
